UNITED STATES PATENT OFFICE.

GEORGE R. OSBORN AND BENJAMIN A. DRAYTON, OF NEW YORK, N. Y.

DESIGN FOR BIRD-CAGE.

Specification forming part of Design No. 7,227, dated March 3, 1874; application filed February 10, 1874.
[Term of Patent 7 years.]

To all whom it may concern:

Be it known that we, GEORGE R. OSBORN and BENJAMIN A. DRAYTON, of the city, county, and State of New York, have invented and produced a new and original Design for a Bird-Cage, of which the following is a specification:

The nature of our design is fully represented by the accompanying photographic illustration, and relates to the upper part or body of

the cage, as indicated by the dotted lines from the point A.

We claim as our invention—

The design for a bird-cage, as shown.

GEORGE R. OSBORN.
BENJ. A. DRAYTON.
